UNITED STATES PATENT OFFICE

2,232,024

ELECTRIC SWITCH

Joseph W. Genari, Columbus, Ohio

Application November 6, 1939, Serial No. 303,114

1 Claim. (Cl. 200—162)

The present invention relates to electric switches of the type generally employed for lighting circuits and has for its primary object to provide a pivoted switch arm adapted for moving into and out of engagement with a pair of contacts to bridge the same for closing the circuit.

A further object is to provide a switch structure of this character which is silent in action, which is efficient and reliable in construction, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which

20 Figure 1 is a front elevational view.

Figure 2 is a vertical sectional view through the switch housing.

Figure 3 is a similar view taken at right angles to Figure 2.

25 Figure 4 is a transverse sectional view taken substantially on a line 4—4 of Figure 3.

Figure 5 is a view in elevation of the switch arm per se shown removed from the housing, and

30 Figure 6 is a perspective view of the pivot pin and switch arm.

Referring now to the drawings in detail, wherein for the purpose of illustration I have disclosed a preferred embodiment of the invention, the numeral 5 designates a switch housing 35 of insulation material having an attaching plate 6 over its front side and forming a cover for the housing, the upper and lower edges of the plate having extensions 7 for attaching to the wall in which the switch is to be mounted.

40 The attaching plate 6 is formed with a vertically extending slotted opening 8, at each side of which is formed oppositely off-set portions 9 forming a bearing for the ends 10 of a pivot pin designated generally at 11. As more clearly 45 illustrated in Figure 6 of the drawings the ends of the pin are rounded and at its intermediate portion the pin is provided with squared sections 12 which are embedded in a handle 13 projecting outwardly from the plate 6. The pivot pin 50 is thus anchored in the handle for actuation thereby. Also projecting laterally from an intermediate portion of the pin 11 is an elongated flat metal arm 14 which is twisted intermediate its ends to provide flatwise engagement with a movable contact designated generally at 16,

which is in the form of a pair of flat metallic arcuate fingers 17 secured crosswise of the free end of the arm by rivets or the like 19. The contact 16 is insulated from the arm 14 and the rivets 19 by means of insulation washers 20, and a retaining plate 18 is provided to prevent pulling of the heads of the rivets through the insulation.

The fingers 17 forming the movable contact are of spring metal and have their extremities 10 spaced apart to form clips adapted for engagement with the upstanding contacts 21 which are embedded in the bottom of the housing 5. The contacts 21 project outwardly from the housing and are provided with terminal screws 22. 15

The inner surfaces of the clips formed on the ends of the fingers 17 are formed with knobs 23 adapted for increasing the frictional engagement of the fingers with the upstanding contacts 21 when moved into engagement therewith. Also it 20 will be noted that the upper ends of the contacts 21 are curved to conform to the arc of the fingers 17.

In the operation of the device it will be apparent that upon the movement of the handle 13 upwardly that the inner end of the arm 14 will be moved downwardly, which carries the movable contact for engaging the upstanding contacts 21 which are adapted to enter between the spaced fingers 17 whereby to bridge the contacts 21 and 30 close the circuit connected therewith. 25

It is believed the details of construction and advantages of the invention will be readily understood from the foregoing without further detailed explanation. 35

Having thus described the invention, what I claim is:

An electric switch comprising a housing, a cover plate for one side of the housing, a switch arm pivoted in the cover plate and including a 40 flat strip having a pin projecting laterally from opposite sides of the strip adjacent one end thereof, a polygonal formation on an intermediate portion of the pin, a handle of insulation material engaging the polygonal formation to 45 oscillate the strip, said strip at its free end being twisted at right angles, a pair of arcuate flat contact members secured flatwise to the free end of the strip with the ends of the contacts arranged in diverging relation and projecting in 50 pairs at opposite sides of the strip to provide spring clips and a pair of stationary contacts in the housing in the path of said clips for engagement thereby.

JOSEPH W. GENARI.
